WINDOW LOCK

Robert L. Sweet, Kansas City, Mo.

Application January 29, 1951, Serial No. 208,329

1 Claim. (Cl. 292—175)

This invention has to do with the field of building and construction and relates more particularly to window structure, the primary object being to provide a novel lock readily attachable to the window sashes and universally adaptable for windows of varying natures, all for the purpose of presenting means to prevent unwarranted entry through the window and capable of automatically locking as the sashes are shifted.

It is the most important object of the present invention to provide a window lock in the nature of a rack and plunger assembly, the rack being mounted upon one of the windows and the plunger being carried by another shiftable window for reciprocation to and from a point engagable with the teeth of the rack.

Another object of the present invention is to provide a window lock particularly adapted for use with conventional windows having a pair of vertically reciprocable sashes, the lock per se including a rack that is mounted upon one of the sashes in an upright condition, together with a manually operable engaging means for the teeth of the rack whereby to eliminate the extent of relative movement of the two sashes in one direction.

Other objects of this invention include the way in which a manually reciprocable plunger is spring-loaded so that the window sashes become locked against relative reciprocation automatically when the sashes are moved to the closed position; the way in which the rack is formed and disposed for simple attachment to one of the window sashes; and the way in which the locking assembly is adapted to not only lock the window sashes completely closed, but to hold the same against further opening from selected open positions as desired.

Many additional more minor objects will be made clear or become apparent as the following specification progresses, reference being had to the accompanying drawing, wherein:

Figure 1 is a side elevational view of a window lock showing the same operably mounted upon the sashes of a window.

Fig. 2 is a vertical sectional view taken on line II—II of Fig. 1 looking in the direction of the arrows.

Fig. 3 is an enlarged, fragmentary, detailed sectional view taken on line III—III of Fig. 1; 50 and

Fig. 4 is an enlarged, fragmentary, detailed sectional view taken on line IV—IV of Fig. 3 looking in the direction of the arrows.

The window structure chosen for illustration 55

of the lock of the present invention is of conventional character and particularly adapted to receive the lock hereof and prevent unwarranted entry as will hereinafter become apparent.

Such illustrated window includes a frame, broadly designated by the numeral 10, adapted to receive an upper sash 12 and a lower sash 14 for separate side-by-side vertical reciprocation within the usual channels 16 and 18 respectively and forming a part of the frame 10.

As is well known in this field, sashes 12 and 14 are provided with proximal horizontal rails 20 and 22 respectively having juxtaposed, complementary, beveled faces that are in interengagement as at 24 when the sashes 12 and 14 are in the closed position illustrated in Figs. 1 and 2 of the drawing. Likewise, each sash 12 and 14 is provided with spaced side rails and it is upon one of such side rails 26 of the upper sash 12 that an elongated rack, broadly designated by the numeral 28 and forming a part of the lock thereof, is operably mounted.

Vertically disposed rack 28 is provided with an opening at each end respectively thereof for receiving screws or like fastening elements 30 serving to mount the rack 28 upon the upper sash 12. One face of the rack 28 is flat and therefore, rests directly upon the inner face of rail 26 as is clear in Figs. 3 and 4 of the drawing, while the opposite face of the rack 28 has a plurality of teeth 32 formed thereon. Each tooth 32 is defined by an angled face 34 and a downwardly facing shoulder 36 as indicated most clearly in both Figs. 2 and 3.

An elongated, horizontally reciprocable plunger 38 is associated with the rack 28 and mounted within the lower sash 14 in alignment with the rack 28. The plunger 38 is provided with a decorative actuating knob 40 on one end thereof and passes entirely through the sash 14 adjacent one uppermost corner thereof for disposition beneath one of the tooth shoulders 36.

It is to be preferred that the horizontally reciprocable plunger 38 be provided with a tubular housing 42 that extends into the sash 14 by mere drilling of a suitable counterbored hole therein and a spring 44 is coiled about the plunger 38 within the housing 42. The housing 42 is provided with a restricted end 43 to present an internal shoulder against which shoulder 46 of plunger 38 bears to limit the movement of the plunger 38 in one direction. One end of the spring 44 bears against the outermost end of the housing 42 while the opposite end of spring 44 engages the annular shoulder 46 on the plunger

38, all for the purpose of yieldably holding the plunger biased toward the rack **28**.

It is noted that the lowermost end of the rack **28** extends to a point overlapping a portion at least of the lower horizontal rail **20** of upper sash **12**, disposing the lowermost shoulder **36** in overlying engagement with the plunger **38** when the sashes **12** and **14** are both closed.

Accordingly, as indicated in Fig. 4 of the drawing, clearance notches **50** and **52** are formed in the horizontal rails **20** and **22** of sashes **12** and **14** respectively.

While tubular housing **42** and its plunger **38** are shown disposed at the point of juncture between rail **22** and a vertical rail **54** forming a part of sash **14**, it is obvious that the same may be lowered on rail **54** if desired to avoid conflict with any fastening elements that may be utilized to interconnect rails **22** and **54**.

In operation, when it is desired to either raise the sash **14** or lower the sash **12**, the operator need merely pull outwardly on the knob **40** to impart reciprocal movement in one direction to the plunger **38** against the action of spring **44**. This releases the innermost end of the plunger **38** with respect to the rack **28** and permits such adjustment of the sashes **12** and **14**. As soon as the sashes are thus adjusted, release of the knob **40** automatically returns the plunger **38** to a position engaging the rack **28** and underlying the shoulder portion **36** of one of the teeth **32**. Such interlocking engagement between plunger **38** and the rack **28**, prevents upward movement of the sash **14** or downward movement of the sash **12** separate from each other. Obviously, as an attempt is made to raise sash **14**, the sash **12** will be moved therewith until it reaches a closed position whereupon further upward movement of sash **14** is prevented.

Conversely, when downward movement of the sash **12** is attempted, the sash **14** will move downwardly therewith until the same comes to rest upon sill **56**, thereby preventing further movement of the sash **12** toward the open position. If an unauthorized person shifts the sashes **12** and **14** away from each other, the plunger **38** will slide along the inclined faces **34** of rack **28** and snap into place beneath successive shoulders **36**, thereby rendering the attempted entry even more difficult. It is further clear that when either or both of the sashes **12** and **14** are partially open, the window will become automatically locked on closing of such sashes because of the spring-loaded plunger **38** and when such sashes are fully closed as shown in Figs. 1 and 2, the plunger will have automatically moved to the position

illustrated in Fig. 3 of the drawing beneath the lowermost shoulder **36** locking both sashes **12** and **14** against opening.

Other advantages emanating from utilization of a window lock structure such as above described, will become clear to those skilled in the art and while details of construction may be varied from the preferred embodiment chosen for illustration, it is desired to be limited only by the spirit of the invention as defined by the scope of the appended claims.

Having thus described the invention what is claimed as new and desired to be secured by Letters Patent is:

In a lock assembly for window structures having a pair of sliding sashes, the side rails whereof overlap varying amounts as the sashes are relatively shifted, a toothed rack adapted to be carried by one of the overlapping side rails, and a counterbored hole through the other side rail; a latch mechanism in the hole and adapted to cooperate with the said rack in preventing relative sliding movement of the sashes, comprising a tubular housing having a restricted end for a portion of the length and contoured to fit the counterbored hole and to present a shoulder adjacent one end thereof, the inside diameter of the housing between the proximal end thereof and the shoulder being substantially less than the inside diameter of the housing between the shoulder and the other end of the housing, a perforated closure for the said other end of the housing, a reciprocable plunger mounted in the housing with the perforation of the closure and the restricted end of the housing serving as bearings therefor, a shoulder on the plunger abutting the shoulder of the housing to limit the movement of the plunger in one direction with one end of the plunger in the latching position behind a tooth of the rack, a spring coiled about the plunger between the shoulder thereon and the closure for the said other end of the housing, and a knob on the other end of the plunger, exteriorly of the housing.
